MOTOR

Ballard F. Snyder, Spokane, Wash.

Application June 22, 1944, Serial No. 541,602

3 Claims. (Cl. 253—17)

This invention relates to a pump and it is one object of the invention to provide a pump which is particularly adapted for pumping water from a stream into a tank or equivalent reservoir from which the water is to be conducted through pipes to farm buildings or other places where it is to be used.

Another object of the invention is to provide a pump wherein water is delivered from the stream into a container which is mounted over a pump cylinder and connected with the piston so that when the container is filled and released it may move downwardly and act as a unit for thrusting the piston downwardly in the cylinder.

Another object of the invention is to provide the container with an outlet at its bottom and a valve for closing the outlet which is connected with a line serving to dislodge the valve and permit water to flow from the container after the piston has made a down stroke, the empty container being then pulled upwardly to its raised position by a counterweight where it is refilled.

Another object of the invention is to provide a latch for releasably holding the container in its raised position, the latch being moved to a releasing position by a weight consisting of a receptacle filled with water overflowing from the main container and the receptacle having an outlet at its bottom normally closed by a valve carried by a pull line so that after the receptacle has moved downwardly and shifted the latch to a releasing position, the receptacle will be emptied and the latch returned to its operative position for securing the container in its raised position.

Another object of the invention is to provide a pump structure in which the various operating elements operate in proper timed relation to each other and reciprocating movement imparted to the pump piston for forcing water through a pipe to a storage tank.

In the accompanying drawings:

Fig. 1 is a sectional view taken vertically through the improved pump structure.

Fig. 2 is a fragmentary view on the line 2—2 of Fig. 1.

Fig. 3 is a fragmentary view on the line 3—3 of Fig. 1.

Fig. 4 is a fragmentary view of the latch for releasably holding the container in its raised position for filling.

This improved pump structure includes a pump cylinder 1 which extends vertically in a casing 2 and has its upper end connected with a pipe section 3 by a coupling 4 and its lower end connected

5 with a pipe 5 by a coupling 6. The pipe 6 and the casing 2 may be of any length and extend into a sump or the like to which water is delivered from a river. An upwardly opening check valve 7 is mounted between the lower end of the cylinder 1 and the coupling 6 so that, as the piston 8 moves upwardly, water may be drawn into the cylinder and the valve closed during downward movement of the piston for forcing the water through the discharge pipe 9. The discharge pipe leads from the pump to a storage tank or other suitable reservoir and has interposed therein a valve 10. This valve 10 has a casing or housing 11 carrying a head 12 at its upper end for connecting it with the pipe 9. The section 13 of the pipe extends upwardly into the valve housing through the bottom thereof and upon its upper end rests a valve ball 14 formed of hard rubber or other suitable material. A cross bar 15 serves to limit upwardly movement of the valve ball so that as the piston moves downwardly in a power stroke, water may be forced through the discharge pipe without interference by the ball. During the upstroke of the piston, the ball seats itself upon the upper end of the pipe section or nipple 13 and holds water in the discharge pipe above the valve 10 during movement of water into the pump cylinder through the valve 7.

10 20 25 30 35 40 45 50 55 The upper end of the pipe section 3 communicates with a sump 16 formed in concrete 17 and having an outlet opening 18 at one side. The concrete is also formed with a recess or pocket 19 having an outlet 20 at one side, this pocket being of less dimensions than the sump 16 and spaced laterally therefrom. Posts or standards 21 rise from the concrete base 17 and are arranged as shown in Fig. 3, so that sleeves 22 at corners of a rectangular tank or receptacle 23 may fit about the posts and slidably mount the tank for vertical movement. At its bottom, the tank is formed with an outlet opening 24 controlled by a valve 25 carrying a gasket 26 which seats against the bottom of the tank and closes the opening 24. The body portion of the valve is of such size that it has sufficient weight to quickly carry it downwardly toward closed position and its lower end is reduced to form a projection or nose 27 which fits tightly in the opening of the gasket 26 and frictionally holds the gasket in engagement with the metal valve. A bridge or yoke 28 is mounted against the under face of the bottom of the tank in crossing relation to the outlet opening 24 and to this bridge is

attached the upper end of the piston rod 29. Referring to Fig. 1, it will be seen that when the tank is in its raised position the piston will be at the top of the cylinder and that, as the tank moves downwardly, the piston will be thrust downwardly in a power stroke. A bridge 30 is mounted across the upper end of the tank and carries a bracket 31 which projects upwardly therefrom and has a bill 32. Through the bracket is mounted a screw or bolt 33 to which is attached one end of a rope or cable 34 which is trained about a pulley 35 and, at its outer end, carries a bucket 36 which rests on the base 17 when the tank is in raised position. This bucket is filled with water until the weight is sufficient to draw the empty tank upwardly to raised position, and the capacity of the tank is such that when it is filled, the weight will overcome the weight of the filled bucket and permit the tank to slide downwardly. The pulleys are carried by a supporting beam 37 which also carries a screw eye 38 to which the upper end of a looped rope 39 is attached. The lower end of the rope is attached to the valve 25 and it is of such length that when the tank moves downwardly and reaches a point close to the base, the rope will be extended its full length and the valve 25 moved to open position so that the water may drain from the tank into the sump, from which it flows through the outlet 18. The piston is forced downwardly in a power stroke as the tank moves downwardly and immediately the tank is emptied, the weight of the filled bucket returns it to its raised position.

A latch or keeper 40 straddles the beam 37 where it is pivotally mounted by a bearing clip 41. Lower ends of the arms of the keeper are brought together and formed with bearings or eyes to receive the shaft 43 carrying a roller 44 for engaging under the bill 32 and support the tank in its raised position. A spring 45 extends longitudinally of the beam 37 at one side thereof and has its inner end engaged with a shackle 46 clamped about one arm of the latch, and the outer end of the spring is engaged with a hooked rod which passes through a bracket 48 and carries a nut 49 so that by turning the nut, tension of the spring may be controlled. This spring yieldably holds the keeper in its operative position but permits it to be swung to inoperative position, in which position the roller moves from under the bill and allows the container to move downwardly.

The keeper is only to be moved to a releasing position when the tank is filled and, in order to do so, the tank has its upper end formed with a spout 50 through which water may overflow from the tank and into a bucket 51. This bucket is carried by a rope 52 which is trained about a pulley 53 carried by a bar 54 and its upper end portion extended horizontally and connected with a shackle 55 clamped about the adjacent arm of the keeper. When the bucket 51 is empty, the spring will hold the roller under the bill 32 and prevent downward movement of the tank, but when the bucket is filled with a predetermined quantity of water, its weight will move the keeper to its releasing position and allow the tank to drop and impart downward movement to the piston. As the bucket 51 moves downwardly, a valve 56 carrying a gasket 57 and attached to a pull line or rope 58 having its upper end connected with a screw eye 59, will be moved out of closing relation to the outlet opening 60 in the bottom of the bucket and water will drain into

the pocket 19. The speed at which water flows from the tank and the bucket is such that the tank makes a down stroke and then returns to its raised position before the keeper moves to its operative position. Therefore, when the keeper returns to its operative position, its roller may engage under the lip 32 and hold the tank raised until the tank is again filled and sufficient water has flowed through the spout 50 to fill the bucket and cause release of the tank. It will thus be seen that the elements of the pump will operate in timed relation to each other and the piston reciprocated vertically to draw water into the cylinder 1 and then force it out through the discharge pipe. The tank is filled with water flowing through a feed pipe which leads from the river and terminates over the tank.

Having thus described the invention, what is claimed is:

- 20 1. In a motor of the character described, a tank movable vertically and imparting a power stroke while moving downwardly, means for delivering liquid into said tank and imparting predetermined weight to the tank, said tank having an outlet controlled by a valve opened as the tank moves downwardly, a member carried by said tank, a bracket carried by said member and having a bill spaced upwardly therefrom and constituting a keeper, an overhead support, guides carried by said support, a cable connected to said bracket and trained about said guides with its outer portion extending downwardly, a weight carried by the outer end of said cable for shifting the empty tank upwardly, and means for releasably holding the tank raised adapted to be moved to releasing position by a weight consisting of a container shiftable downwardly to actuate said means and disposed in position to be filled and weighted by liquid overflowing from said tank.
- 25 2. In a motor of the character described, a tank movable vertically and imparting a power stroke while moving downwardly, means for delivering liquid into said tank and imparting predetermined weight to the tank, said tank having an outlet controlled by a valve opened as the tank moves downwardly, a member extending across said tank, a bracket carried by said member and having a bill spaced upwardly therefrom and constituting a keeper, an overhead support, guides carried by said support, a cable connected to said bracket and trained about said guides with its outer portion extending downwardly, a weight carried by the outer end of said cable for shifting the empty tank upwardly, a latch for holding the tank raised consisting of a yoke disposed about the support and pivotally mounted for swinging toward and away from the bracket, said yoke extending downwardly from the support, a roller rotatably carried by lower ends of the arms for engaging under the bill and supporting the tank in its raised position, a spring anchored to the support and connected with one arm of the yoke for yieldably holding the latch in operative position, and means for moving the latch to releasing position actuated by a weight consisting of a container adapted to be filled by liquid overflowing from the tank to impart predetermined weight thereto.
- 30 3. In a motor of the character described, a tank movable vertically and imparting a power stroke while moving downwardly, means for delivering liquid into said tank and imparting predetermined weight to the tank, said tank having an outlet controlled by a valve opened as the

tank moves downwardly, a cross bar carried by said tank, a bracket carried by said cross bar and having a bill spaced upwardly therefrom and constituting a keeper, an overhead support, guides carried by said support, a cable connected to said bracket and trained about said guides with its outer portion extending downwardly, a weight carried by the outer end of said cable for shifting the empty tank upwardly, a latch for holding the tank raised consisting of a yoke disposed about the support and pivotally mounted for swinging toward and away from the bracket, said yoke extending downwardly from the support, a roller rotatably carried by lower ends of the arms for engaging under the bill and supporting the tank in its raised position, a spring anchored to the support and connected with one

5 arm of the yoke for yieldably holding the latch in operative position, a bracket carried by the cross bar, a guide carried by said bracket, a cable carried by one arm of the yoke and trained about the guide with its outer portion extending downwardly therefrom, a receptacle at the lower end of the cable, and a spout extending from the upper end of the tank for directing liquid overflowing from the tank into the receptacle and 10 creating predetermined weight for moving the latch to releasing position and allowing the tank to move downwardly and imparting a power stroke, said receptacle having an outlet opening at its bottom adapted to be moved to open position as the receptacle moves downwardly.
